CLAIM

The ornamental design of a closure device with screw thread, as shown and described.

DESCRIPTION

FIG. 1 is a perspective view of a closure device with screw thread showing my design;

FIG. 2 is a side elevational view thereof, the opposite side view being a mirror image thereof;

FIG. 3 is a front elevational view thereof;

FIG. 4 is a rear elevational view thereof;

FIG. 5 is a top plan view thereof;

FIG. 6 is a bottom plan view thereof; and,

FIG. 7 is a cross-sectional view thereof taken along lines 7—7 in FIG. 1.
